UNITED STATES PATENT OFFICE.

WILLIAM H. LJUNGBDAHL, OF BEND, OREGON, ASSIGNOR TO ALBERT W. COOPER, OF PORTLAND, OREGON.

TUNNEL KILN.

Continuation of application Serial No. 591,085, filed September 28, 1922. This application filed January 19, 1926. Serial No. 82,323.

My invention relates to apparatus for cooling charcoal or other matter treated. This application is a continuation of my forfeited application, Serial No. 591,085, filed September 28, 1922. The carbonized material is transferred from the retort or kiln after the carbonizing process is completed and my invention relates more particularly to the construction of a cooling chamber employed in the process of extinguishing and cooling incandescent charcoal. In the accompanying drawing which is by reference made a part of this specification, Fig. 1 is a vertical longitudinal section of the retort and cooling chamber. The retort or kiln may be constructed for instance according to patent of Aminoff No. 748,457, but it is also understood that it is not confined to this type of kilns only. Fig. 2 is a plan view of the cooling chamber and a part of the kiln or retort. Fig. 3 is a vertical longitudinal section of the cooling chamber and part of the kiln. Similar figures refer to the similar parts throughout the several drawings.

When the material has been completely charred or treated in the kiln it is transferred in a conveyor 13 from the kiln or retort into the lock chamber 14 and then to the cooling chamber 2 through the entrance door 3 in Figs. 1 and 3. The cooling chamber consists of a horizontal closed chamber through which, in this case, the material is moved from left to right and a current of gas circulates about the material contained in the conveyor, in the opposite direction to the movement of the material. The gas used in the cooling chamber is derived partly from the material in the cooling chamber and partly from the kiln or retort. The cooling chamber 2 is equipped with a track 15 as shown by the dotted line in Fig. 2 for the conveyors containing the charred material. Said cooling chamber is also equipped with lock chamber or exchange chamber 16, provided with doors 4. The lock chamber is of sufficient size to contain one conveyor.

The cooling chamber 2 has an inclined roof 5 and is provided with pipes 6 on the two outer sides of the chamber. Said pipes open into the chamber at points indicated by 7 and 8 in the cooling chamber. At the end of the cooling chamber that is close to the kiln said cooling pipes open into the

cooling chamber at a point 7 close to the roof. At the other end of the cooling chamber closed to the entrance of the lock chamber 16, said cooling pipes open into the chamber at the point 8 but here close to the floor. The cooling chamber is also connected with the retort by means of a pipe 10 equipped with a valve 9. By means of this connection gas can be drawn from the kiln to the cooling chamber where it is used as a cooling medium, after it has sufficiently cooled in the manner later described. It will be understood that this gas is indifferent to incandescent charcoal. If in the apparatus shown, the cooling chamber 2 is of sufficient size to contain four conveyors containing the material treated in the kiln, a conveyor may be taken out every two hours, thus the total time required to cool the charcoal is eight hours. After the cooling process of eight hours this charcoal is absolutely safe to be handled in the outside atmosphere. Other known methods for cooling charcoal require a time of twenty-four to forty-eight hours and more. Of course it is understood that every time a conveyor is removed from above mentioned cooling chamber, another conveyor with incandescent coal is transferred from the kiln through the lock chamber 14 and thence to the cooling chamber 2.

The gas in the cooling chamber 2 is withdrawn from said chamber at a point 7 near to the roof of the cooling chamber where it is the highest. It is then conveyed through the cooling pipes by means of fans 11 forcing the gas into the pipes 6. These pipes pass through a water or spray from the perforated pipes 12 as shown in Fig. 2. The gas thus becoming cooled is then forced back into the cooling chamber by the fans 11 and enters at a point 8 and close to the floor as shown in Fig. 3. The traveling direction of the gas is as indicated by the arrows in Figs. 2 and 3. During the passage of the gas from the points 8 where it is forced into the cooling chamber, it travels in a direction opposite to that in which the conveyor containing the material treated, moves, thus the cool gas first strikes the material in the conveyor which has been in the cooling chamber for the longest period of time, then the cooled gas strikes the hot-

ter charcoal and becomes warmer and slowly rises to the roof of the cooling chamber and is again withdrawn forming a continuation of the cooling process. The arrangement of the inclined roof and the advantage thereof can readily be seen and understood, being that a warm gas always rises. The process as a whole is carried on continuously and until the material treated has been sufficiently lowered in temperature so that it can be removed from the cooling chamber without danger of ignition on being exposed to the atmosphere.

The time required for extinguishing and cooling by this process is much shorter than in any method now in use.

Having fully described my invention I claim and desire to protect by Letters Patent:

1. In a tunnel kiln in which the kiln chamber comprises a heating compartment and a cooling compartment adapted to be successively traversed by the material passing through the kiln and includes means for separating said compartments from one another, the improvement which consists in means for circulating a cooling gas through a closed circuit of which the cooling com-

partment constitutes a part, means for cooling said gas as it passes through the circuit, and means independent of said separating means for optionally introducing gas into said cooling compartment from the heating compartment.

2. In a tunnel kiln in which the kiln chamber comprises a heating compartment and a cooling compartment adapted to be successively traversed by the material passing through the kiln and includes means for separating said compartments from one another, the improvement which consists in means for circulating a cooling gas through a closed circuit of which the cooling compartment constitutes a part, means for cooling said gas as it passes through the circuit, and valve controlled means independent of said separating means for optionally introducing gas into said cooling compartment from the heating compartment, said cooling compartment having an inclined roof and an outlet port for the gas located adjacent the higher end of the compartment.

In testimony whereof, I have hereunto set my hand.

WILLIAM K. LJUNGBDAHL.
